UNITED STATES PATENT OFFICE.

CHARLES E. OVENSHERE, OF MINNEAPOLIS, MINNESOTA, ASSIGNOR TO THE MINNEAPOLIS KNITTING WORKS, OF SAME PLACE.

DESIGN FOR A CHILD'S WAIST.

SPECIFICATION forming part of Design No. 31,456, dated August 22, 1899.

Application filed June 3, 1899. Serial No. 719,309. Term of patent 14 years.

To all whom it may concern:

Be it known that I, CHARLES E. OVENSHERE, of Minneapolis, county of Hennepin, State of Minnesota, have invented a certain new and useful Design for a Child's Waist, of which the following is a specification, reference being had to the accompanying drawings, forming a part thereof.

In the drawings, Figure 1 is a perspective view of the front of a child's waist. Fig. 2 is a similar view of the rear of the waist.

The design consists in the waist having a series of strengthening or bracing bands or tapes, two of which, A A, passing over the shoulders, extend down the front and back of the waist to the bottom thereof.

The design for the back is completed by a band or tape D, intermediate to the bands

A A, divided at its upper end for a considerable distance, the diverging sections being merged into the bands A A at points near the shoulder portions of the waist.

The design is completed by bands or tapes E E, arranged under the armholes, divided at their upper ends and joined to or merged into bands A A at points opposite the junction of said bands A A with the band D.

I claim as my invention—

The design for a child's waist, substantially as shown and described.

In witness whereof I have hereunto set my hand this 27th day of May, 1899.

CHARLES E. OVENSHERE.

In presence of—

C. G. HAWLEY,
RICHARD PAUL.
